UNITED STATES PATENT OFFICE.

ANTON J. ROLLERT, OF CHICAGO, ILLINOIS, ASSIGNOR TO THEODOR A. KOCHS, OF SAME PLACE.

DESIGN FOR A BARBER'S CHAIR.

SPECIFICATION forming part of Design No. 20,927, dated July 7, 1891.

Application filed June 15, 1891. Serial No. 396,380. Term of patent 3½ years.

To all whom it may concern:

Be it known that I, ANTON J. ROLLERT, a citizen of the United States, residing at Chicago, in the county of Cook and State of Illinois, have invented a novel Design for Barber's Chairs; and I do hereby declare the following to be a full, clear, and exact description of the invention, such as will enable others skilled in the art to which it appertains to make and use the same.

The design consists in the novel configuration and ornamentation for a barber's chair, as hereinafter described, and illustrated in the drawing.

15 The drawing is a perspective view of a barber's chair embodying my design.

Referring to said drawing, A indicates the base of a chair, and B the body portion thereof. The said body portion is provided in a 20 familiar manner with the seat, back, headrest, and arms. At their forward ends the arms are rounded and curved upwardly and backwardly, and are then widened and ribbed and curved downwardly until they meet the 25 arms. From the forward ends of the arms a

fancifully curved and ornamented piece extends downwardly to the front corners of the seat. On the rear edges of these pieces are circular ornamented projections, and between the upper edges of these circular projections and the seat are ribbed and ornamented pillars. The back of the chair at about the rear ends of the arms has a raised scroll, and above this scroll the back is scalloped.

The parts of my design, when formed and 35 assembled as shown and described herein, serve to add to the appearance of a barber's chair and ornament the same in a highly-effective, symmetrical, and harmonious manner, which is agreeable and pleasing to the 40 eye.

I claim as my invention—

The design for a barber's chair, substantially as shown and described.

In testimony whereof I affix my signature in 45 presence of two witnesses.

ANTON J. ROLLERT.

Witnesses:

JOHN FISCHBACK,
CHARLES E. SHAW.
